BRASSIÈRE

Henry H. Bruderlin, Venice, Calif.

Application December 2, 1946, Serial No. 713,546

6 Claims. (Cl. 2—42)

1
This invention relates to brassières and is directed more particularly to brassières of the so-called "strapless" type which are supported on the body of the wearer without the assistance of the usual straps passing over the shoulders and attached to front and rear portions of the garment.

There are several varieties of strapless brassières already known but none of them has been found to be entirely satisfactory. The simplest type is little more than a conventional brassière with the shoulder straps removed and is held in place by high circumferential tension which tends to pull the cup portions out of shape and deform the breasts. In order to insure that it does not slip downward, it is necessary to provide tie material at the front center of the garment at a lever near the top of the cups. Consequently this type is not suitable for use with dresses having deep necklines since the tie member would be visible.

Another type makes use of substantially the same basic member described above but includes wire stays of various kinds adapted to stiffen or support local areas of the brassière. While this type is generally more satisfactory, it is not a complete solution to the problem because it is likewise maintained in position by circumferential tension in the fabric which causes distortion. Since the tension is tending to distort the fabric and the stays are tending to hold it in shape, it is obvious that there is a strong tendency for the fabric to fail and tear away where the load is transferred from the fabric to the wire.

Another drawback of all types of strapless brassières known up to this time is that they require a band across the back, usually including a detachable fastener in the center of the back. In addition to the inconvenience of such an arrangement, the back strap, in the case of a bathing suit brassière, precludes the possibility of building up an even coat of tan across the back. Consequently, a woman who wears a bathing suit provided with such a brassière is unable to wear a backless evening gown because of the unsightly mark produced.

The present invention overcomes all of the difficulties presented by previous types of brassières and also possesses additional advantages

and features outlined below. In the new type brassière there is provided for the first time a completely self supporting frame which does not rely for any of its support on the fabric of the brassière proper and which does not place any strain on the fabric. Moreover it eliminates the back strap together with its fastening member mentioned above and leaves almost the entire width of the wearer's back exposed to the sun, in the case of bathing suit brassières, so that a uniform suntan may be obtained.

The frame is complete in itself and can be shaped to provide the most desirable outline, including a very low center section suitable for dresses with deep necklines. Means are provided for varying its peripheral and vertical extent so that a single frame will encompass a wide range of sizes. Another feature of one form of the device is that the right and left halves of the frame are pivotally connected together so that the frame can flex to accommodate all types of body movements without becoming displaced and without interfering with or restraining such movements.

25 The frame is of generally C-shape conforming to the contours of the body and is formed of resilient material by virtue of which it resiliently grips the body exerting a slight pressure at all points. Experience has shown that it is far more comfortable than any type which requires a back strap.

Since the frame is basically complete in itself it is necessary to have only one frame on which any desired cover may be mounted in a few moments. The covers are made in pairs, each covering only one half of the frame. Each cover is provided with a pocket of the same shape as the frame, having an open mouth into which the free end of the frame may be inserted, whereafter the frame is collapsed and pushed into the pocket. The frame then expands to its original shape and the cover is firmly held in place against any accidental displacement.

45 The frame may be made of wire or of plastic such as "Lucite." The latter is quite resilient and has a low spring rate so that, in the un-stressed state, it may be formed into a completely closed loop with the free ends overlapping by about a quarter of the developed length of the

frame. In this form it takes up very little room and can be conveniently packed for traveling. When it is spread sufficiently to apply to the body the pressure is not uncomfortable because of the low spring rate.

Although the invention is intended primarily to provide a strapless brassière it is within the ambit of the invention to provide the usual shoulder straps if desired. The straps are useful where very substantial uplift is required, and at the same time the open frame provides comfort and freedom of action which is unattainable in any brassière requiring a back strap. Simple safety ties may, of course, be provided on the bathing suit type of brassière for temporary use during strenuous activities, such as diving.

Other features and advantages will become apparent as the description proceeds.

While the invention may take numerous forms, those which are presently preferred are illustrated in the accompanying drawings in which:

Fig. 1 is a three-quarter rear view in perspective of one form of the brassière frame of this invention with the cover removed;

Fig. 2 is a rear elevational view of said frame with the cover in place, but with a portion thereof broken away;

Fig. 3 is a top plan view;

Fig. 4 is a side elevational view illustrating the means for obtaining vertical adjustment;

Fig. 5 is a sectional view taken on line 5—5 of Fig. 2;

Fig. 6 is a sectional view taken on line 6—6 of Fig. 1;

Fig. 7 is a detail view of an end portion of the frame of Fig. 1, showing a modification thereof;

Fig. 8 is a top plan view of a plastic frame similar to Fig. 1 coiled into a closed loop in unstressed condition;

Fig. 9 is a developed view of a portion of a modification made from sheet material;

Fig. 10 is a partial front elevational view of another modified form of the frame of Fig. 1; and

Fig. 11 is a sectional view on line 11—11 of Fig. 10.

Referring first to Fig. 1, the basic frame, generally indicated by the numeral 10, comprises an upper, thin or narrow, elongate element 12, and a similar lower element 14. The latter lies substantially in a horizontal plane and is generally C-shaped in plan, as is apparent in Figs. 2, 3 and 4. The upper element lies more or less vertically above the lower element and is similarly C-shaped in plan. However, in elevation, it is seen that this element is divided into right and left hand medial portions 16 and 18 having an upwardly arched shape to conform to the breasts of the wearer.

The adjacent ends of the arched portions are provided with interengaging bridge members 20, 22, each provided with a loop or eye 24 for rotatable and slidably engagement with the cooperating straight member. The telescoping connection provides lateral or peripheral adjustment so that one frame will serve for several sizes and will permit any desired amount of separation of the breasts. The pivotal nature of the connection, together with the resilience of the material of the frame, permits axial twisting and flexure to follow various body movements without imposing undue restraint. The specific construction of the connection will be apparent from an examination of Fig. 5. When the frame is unstressed the connection may be adjusted readily

but tends to bind in adjusted position when the frame is applied to the body of the wearer.

The lower element is provided with a similar connection which can be adjusted over a wider range to insure a snug fit in every instance.

The outer free ends of the upper and lower elements converge toward each other as seen in Fig. 4 and are curved to form a C-shape, as best illustrated in Fig. 3, conforming to the sides and back of the wearer.

The entire frame may be made of resilient material, such as wire, and in its free, unstressed state it encloses a cross sectional area somewhat less than that of the body. It is applied by opening it out far enough to slip around the body, with member 14 below the breasts and member 12 above them. Since the frame is resilient, it tends to return to its original size and therefore exerts a firm but resilient grip on the body sufficient to hold it securely in position. The pressure is distributed thruout the entire length of the frame and the result is an unusually comfortable support.

The right and left halves of the frame may each be formed from a single length of wire having an integral loop 26, 28 at the free end of the frame. In order to obtain added resiliency, the wire in the loop portions may be flattened in cross section as shown in Fig. 6. This also makes it possible to bend the loop portions more readily to make slight modifications in the curvature of the frame.

A modification of the free end portions of the frame is illustrated in Fig. 7 in which the integral loop is replaced by a piece of sheet material 30, preferably metal, rolled over the individual ends of the elements 12 and 14 at 32 and 34, and secured thereto by soldering, brazing, or other suitable means. The thin sheet, being resilient and bendable, serves the same purpose as the integral loop.

The brassière is completed by the provision of suitable covering material mounted on the frame in a novel manner. The cover is preferably of fabric such as is generally used in conventional brassières. It is made in right and left hand halves 36 and 38, each of which includes the usual cup portion and additional material passing around the side to the back. To this piece of material is attached a second piece 40 stitched to the first piece along a line corresponding to the outline of the frame and forming a pocket closed at all point except the mouth 42 at the end of neck 44. The pocket thus formed is considerably wider intermediate its ends than it is at the mouth. To assemble the parts in position the frame is collapsed and the free end portion 26 or 28 is inserted into the open mouth 42. The balance of the frame follows thru and is then allowed to expand inside the pocket, making an assembly which is secure against accidental displacement. The cover for the other half is similarly mounted. The neck of each cover extends beyond the mid point of the frame so that the two overlap, and they may be secured together by any conventional snap fastener 46.

A modification of the brassière so far described has been found to be desirable in cases where very substantial uplift is required. In such cases, shoulder straps 45 are provided in the usual manner. The straps hold the frame and cover as high as desired, and yet the freedom afforded by the open back makes this arrangement far superior in comfort and support to a conventional

type. A neck strap can be attached to the bridge section to get the same beneficial result for bathing suit wear.

Altho the frame as disclosed has a very tenacious grip, there is a slight possibility of displacement, when used as a foundation for a bathing suit brassière, during periods of very strenuous activity such as diving. For these circumstances, tie straps 47 are provided to be tied across the back temporarily. When not needed, they may be readily tucked away out of sight between the free ends of the brassière and the body.

It is desirable to provide means for controlling the distance between the upper and lower elements as a further element of producing a satisfactory fit. This is accomplished by means of a tie member 48, shown in Fig. 4, which may be a ribbon passing around the lower element and the bridge between the arched portions. When the elements have been drawn together to the desired degree the ribbon is tied to maintain the adjustment. It may be tied directly over the frame or positioned outside the covers after they are in place to serve an added decorative function.

In a modified form of the invention the frame generally illustrated in Fig. 1 may be made of a strip of plastic material, such as "Lucite." The strip is preferably of rectangular cross section similar to the showing of Fig. 6. Dimensions of the order of $\frac{1}{16}$ " by $\frac{5}{16}$ " have been found to give very satisfactory results with this material. The plastic frame may be made without the adjustable connections 20, 22. Since it has a greater resiliency and lower spring rate than wire it will flex more readily under the same conditions.

The plastic frame is a very desirable type for those who travel. It can be formed in its un-stressed state so that it forms a closed loop with the ends overlapping to the extent of about a quarter of the developed length of the frame as illustrated in Fig. 8. Because of its resiliency and low spring rate it can be spread far enough to encompass the body without exerting excessive pressure. It is obvious that a frame of this type can be conveniently packed in a small space in a traveling bag.

Fig. 9 illustrates a variation of the invention in which the entire frame is made of a single piece of sheet material 50, which may be metal or plastic. Breast openings 52 are cut in the sheet and the free ends 54 are curved to form a C-shape as in the previous modifications. Additional ventilation openings may be provided as desired.

In a further modification of the invention, as illustrated in Figs. 10 and 11, the frame elements may be formed of wire which is relatively rigid. In this case the upper frame elements 56 and 58 are provided with slotted ends, as at 60, 62, into which is inserted a strip of resilient metal 64, which may be soldered, brazed or otherwise secured thereto. The lower elements 66, 68 are joined to strip 70 in the same manner. This type of frame is applied to the body in the same way as the other types but practically all of the yielding takes place in the strips 64 and 70. The frame elements are, however, resilient enough to be collapsed for assembly with the covers.

One of the important advantages of the invention is that a single frame may serve as the basis of any number of different brassières, since one pair of covers may be replaced by another in a few moments. Since the covers are compara-

tively simple and inexpensive, a substantial saving is thus effected.

The spring biasing effect, which is common to all of the forms disclosed, provides the most comfortable brassière so far devised, and one which places the least restraint on various body movements.

While various preferred forms of the invention have been illustrated and described hereinabove, it will be apparent that many changes and modifications may be made without departing from the invention, and it is intended that all such changes and modifications shall be embraced within the scope of the following claims.

I claim:

1. A self supporting strapless brassière comprising: a generally C-shaped frame, the medial portion of which includes upper and lower laterally extending wire elements curved in plan view to conform to the body of the wearer adjacent the breasts, each of said elements being structurally continuous across the plane of symmetry and thruout their lengths; the upper element having two sections, one at each side of the plane of symmetry of the frame arched upwardly away from the lower element to define therewith a pair of breast receiving openings; the free ends of said elements being more sharply curved in plan view than the medial portion to engage the sides and back of the wearer and converging toward each other and being joined at their extreme ends; the juncture of said free ends being below the midpoint of the medial frontal portion of said frame; said frame being spring biased to resiliently grip the body and retain itself in position thereon; and breast supporting covering material mounted on said frame in such manner as to prevent direct contact between said frame and the body.

2. A brassière as claimed in claim 1 in which said upper and lower elements are each divided into two sections; each pair of sections being pivotally joined on an axis substantially tangent to the center of said frame.

3. A frame for a brassière comprising: symmetrical right and left frame members of resilient material; each member having upper and lower spaced terminal portions adapted to meet substantially in the plane of symmetry of said frame; said upper terminal portions being pivotally connected to each other and said lower terminal portions being pivotally connected to each other; whereby said frame is capable of flexural and pivotal motion to follow the movements of the body.

4. A frame for a garment comprising: four elements of filamentary resilient material extending laterally from the plane of symmetry of the frame and slightly curved to conform to and contact the body adjacent the breasts; those elements defining the upper margin of the frame being upwardly arched away from the plane of symmetry and those elements defining the lower margin of the frame lying substantially in a horizontal plane; said upper and lower elements forming between them a pair of breast receiving openings; each element extending to one side of the plane of symmetry being directly connected to an element extending to the other side of said plane; the free ends of said elements being more sharply curved to conform to and contact the sides and back of the body of the wearer; each pair of elements extending to one side of the plane of symmetry being joined at their extremities.

5. A frame for a garment comprising: a unitary structure of resilient material having substantially a C-shape in horizontal projection; the medial frontal portion lying substantially in a vertical plane and having the general form of a figure 8 in said plane; the lower edges of said figure being substantially flat and lying in a horizontal plane; and the arched end portions of said frame gradually tapering down to relatively small free ends lying substantially in said horizontal plane and well below the mid-point of said medial frontal portion.

6. A frame for a garment comprising: a unitary structure of filamentary resilient material, all elements of said structure being directly physically connected to each other and structurally continuous across the plane of symmetry from end to end of said frame, and having the general form of a figure 8 in vertical projection and being generally C-shaped in horizontal projection to conform to and resiliently grip the body of the wearer; the opposed ends of said structure being tapered down to relatively small free ends ly-

ing below the mid-point of the medial frontal portion of said structure.

HENRY H. BRUDERLIN.
